UNITED STATES PATENT OFFICE.

HOWARD A. GLENN AND LOY S. DROMGOLD, OF CHICAGO, ILLINOIS.

HOPPER FOR REFRIGERATING CARS.

Application filed February 8, 1926. Serial No. 86,822.

This invention relates generally to refrigerating or refrigerator cars, but has particular relation to a hopper which is mounted in the top of a car, near one of the ends 5 of the latter and to one side of the running-board, and used for the insertion of salt and ice, and for other purposes.

Heretofore, and up to the present time, it has been the common or general way, and 10 so far as we are aware, the only method of constructing and applying the hoppers to cars; to do the work of constructing the hoppers and placing the same in position on the car roof or top, and by carrying out 15 the following modus operandi, to-wit;—

The metal pieces of which the hoppers are constructed, are made on the ground or in the shop, into galvanized parts of the proper dimensions to fit the opening in the car 20 roof when joined together, and are then passed up to the workman on the roof of the car. This workman, in order to weld or solder the edges of the said galvanized pieces to join them together, prepares or 25 exposes them for solder or the welding operation. After such preparation has been performed, he proceeds to join said edges while they are in the opening of the car roof. These junctures are more or less 30 crude, rough and not galvanized for the reason they cannot be so treated while the hopper is located in the opening of the car roof, and therefore are directly subjected to the effect of the salt and the water 35 from the ice and are liable to corrode and be otherwise damaged, thus rendering a short lived hopper.

In order to give durability and long wearing effect to the aforementioned kind of hoppers they must be completely coated with protecting material or galvanized, and in order that this may readily be done and to save labor, time and expense in the construction and application of such hoppers, we 45 have invented certain new and useful improvements in the hoppers and in the method of their application and simplified them to a great extent.

We accomplish this by means of our 50 method of construction and application of the hoppers, which will be more readily understood when read in conjunction with

the accompanying drawing, which illustrates an embodiment of our invention and in which—

Fig. 1, is a top plan view of a portion 55 of the roof of a refrigerating car showing a hopper embodying our invention mounted in a suitable opening therein.

Fig. 2, is a transverse sectional view taken 60 on line 2, 2, of Fig. 1, and

Fig. 3, is a longitudinal sectional view taken on line 3, 3, of Fig. 1, looking in the direction indicated by the arrows. Like 65 numerals of reference refer to similar parts throughout the different views of the drawing.

Referring now to the drawing the reference numeral 5, designates a portion of the top or roof of a refrigerating or refrigerator 70 car which is provided at its longitudinal middle with a running-board 6 as usual. Near one end of the car top and at one side of the running-board the top or roof 5, is provided with an opening 7, which opening 75 is preferably rectangular in shape and has a similarly shaped frame 8, fitted and secured therein. This frame is of an open character and as shown projects at one of its edges slightly above the top or roof 5, and at its other or lower edge slightly below 80 said roof. Below the frame 8, and extending longitudinally and horizontally with respect to the car body is one of the supporting beams 9 which may be joined at its ends 85 to the ends of the car body in the usual or well known way.

Our hopper, which is preferably made of sheet metal is designated as a whole by the numeral 10, and consists of a pair of end-pieces 90 11, and a pair of side-pieces 12, which may be fitted together to form a rectangular open ended hopper as it is clearly shown in the drawing, or in other words so as to form a hopper with its top and bottom open. The 95 end-pieces 11, of the hopper are each provided at its lower edge with an inverted U-shaped cut-a-way portion 13, from which is extended inwardly of or between the sides 11, a horizontal flange 14, to rest on the upper and side surfaces of the beam 9, so as to assist in holding the hopper in position.

It will be observed that the end-pieces 11, as well as the side-pieces 12, constituting the

hopper, are each provided with an outwardly extended rectangular flange 15, which is down turned as at 16, and has on its free end a base flange 17, provided with spaced openings for rivets or fastening devices 18, used for securing the base flange to the upper surface of the roof 5, as is clearly shown in the different views of the drawing.

Now, our method of constructing the hopper and preparing it for application within the frame 8, is all accomplished on the ground or in a shop, which enables us to provide hoppers of such unitary character as to be kept in stock ready for sale or use. That is to say the end and side pieces 11, and 12, respectively are first cut to the proper dimensions, are then soldered or welded together at their meeting edges, and the requisite top and lower edges of the pieces constituting the hopper are provided with the flanges 15, and 17, as well as with the cut-away parts 13, and flanges 14, around the same.

The thus completed structure is then thoroughly galvanized in all of its parts and is ready to be placed in the frame 8, where it can be firmly held in place by means of rivets or fasteners 18 extending through the openings therefor in the flange 17, and into the roof around the perimeter of the opening 7, therein. In this operation it will be understood that the flanges 14, will stride the beam 9, and rest upon the same, thereby assisting in supporting the hopper.

By using our construction and method of applying the hopper, it will be understood that every portion of the latter will be thoroughly galvanized whereas in the old method the solder at the meeting edges of the pieces, or the welded ungalvanized joints will be exposed to the action of salt and the

water from the ice and other material which may be passed through the hopper.

In Fig. 1, of the drawings it will be seen that the end pieces 11, of the hopper, are of somewhat greater length than the side-pieces 12, of the same, and as the pieces 12, are located in parallelism with the sides of the car body they are designated as above.

While we have shown in the accompanying drawing, and described in the specification, the hopper as being made of a plurality of pieces joined together, thereby forming a unit, yet, we do not desire to be limited to such construction, as we may form the hopper of a single sheet or piece of material into the desired shape and then galvanize it as a unit.

Having thus fully described our invention, what we claim as new and desire to secure by Letters Patent is:

1. The herein described method of constructing a hopper for refrigerating cars, which consists in making the hopper of the proper dimensions and then galvanizing the whole as a unit before mounting it in position.

2. The herein described method of constructing a hopper for refrigerating cars, which consists in making the pieces of a hopper of the proper dimensions, then joining them together, and finally galvanizing the said parts as a unit.

3. The herein described method of constructing and applying a hopper for refrigerating cars, which consists in making the pieces of a hopper of the proper dimensions, then joining them together at their edges by welding and then galvanizing the said parts in their unitary form.

HOWARD A. GLENN.
LOY S. DROMGOLD.
